UNITED STATES PATENT OFFICE.

MORRIS C. NELSON, OF ROCK ISLAND, ILLINOIS.

AUTOMATIC ELEVATOR CONTROL.

Application filed December 10, 1925. Serial No. 74,635.

My invention has reference to an automatic elevator control, and relates more specifically to devices of that kind which are arranged to be electrically operated. Through the use thereof it is possible for the operator of the elevator to select the floor at which he wishes the car to stop, and set the mechanism accordingly, so as to have the car stop at the desired point, without further attention on his part. This is accomplished by means of a series of conductors, one for each floor at which the elevator is to stop, through which conductors circuits may be formed by apparatus carried by the elevator, such conductors being provided with breaks, or gaps at the various floors, resulting in a break in the circuit, and consequent stoppage of the car.

In connection with said apparatus is employed a brake operating device, of a common type, which is automatically operated to cause an instant stoppage of the elevator, coincidently with the interruption of the current through the conductor.

25 In the drawings:—

Fig. 1 is a vertical section, showing a fragmentary part of the invention.

Fig. 2 is an enlarged detail of one of the contact devices.

30 Fig. 3 is a vertical section through the panel 30.

Fig. 4 is a diagrammatical view of a series of conductors, or rails, such as is used in the invention.

35 Fig. 5 is a detail of the panel 26, from the front thereof.

Fig. 6 is a front view of the panel 30 detached.

Fig. 7 is a diagrammatic view of the invention, including the wiring system therefor.

40 The showing in Fig. 4 is for use in a building having eight floors for elevator stops, and said floors are numbered upwardly from 1 to 8, inclusive. In Fig. 1 the numeral 11 indicates the front wall of an elevator shaft, 12 the rear wall, and 13 the elevator movable vertically of said shaft, and supported by a cable 14, passing over a pair of pulleys 15 on a support 16, said cable extending 45 downwardly to a drum 17 at the bottom of the shaft, upon which the cable is wound. Connected with the drum 17 is a brake-drum 18, encircled by a band 19, operable by an electrically controlled device at 20, in circuit with a motor 21, by which the drum 17 is driven. The motor 21 is connected with

a source of electrical power, shown at 22, by means of a wire 22*.

Secured to the wall of the shaft in rear of the elevator is a series of rods 23, one for each floor in the building, which rods provide rails for a series of rollers 24, mounted on posts 25, fixed in a panel 26, attached to the rear part of the car. Wires 27 connect the posts 25 respectively with a plurality of terminals 28, fixed on an arc-shaped board 29, attached to a panel 30, supported in the car 13, convenient to the hand of the operator. Pivoted on the panel 30 is a lever 31, adapted for selective engagement with one or other of the terminals 28. A wire 32 connects the lever 31 with the source of power at 22, such wire being passed through a push-button switch, as shown at 33, by means of which the apparatus may be cut off from the source of supply, if desired. Wires 34 connect the upper ends of the rods 23 with the motor 21, while other wires 35 lead from the lower ends of said rods to said motor, said wires being also in circuit with the 50 brake control device 20. Each of the rods 23 is divided into two parts by means of insulator sections 36, which form gaps in the several rods, and cause a break in the circuit caused by the contact therewith of the rollers 24. Said gaps are formed in staggered relation with each other, so as to conform to the several floors, as shown in Fig. 4.

The sections of said rods above the insulators are in a circuit independent from the sections below the same, the upper circuit being connected with the motor in such a manner that a contact of one of the rollers 24 with one of the rods will cause the motor to operate to move the car downwardly, 55 and the lower sections are connected with the motor so as to cause an upward movement of the car upon the contact being made with said lower sections.

In starting the elevator, the operator moves the lever 31 to a contact with the terminal 28 corresponding with the floor at which it is desired to have the car stop. Assuming such car to be at the first floor landing, the contact of the lever with one of the terminals 100 closes a circuit through the roller 24 connected therewith and the rod 23 upon which said roller operates. This starts the motor in a direction to move the elevator upwardly, 105 which movement is continued until the roller comes in contact with the insulated section of the rod, whereupon the circuit is broken, 110

and the motor ceases to operate. Coincidentally therewith the brake is set, and the elevator stopped. For example, if a connection has been made with the rod 23 at 5 the extreme left in Fig. 4 the elevator will be carried to the eighth floor, and by making a connection with the rod at the extreme right it will move downwardly again to the lower floor. The rod for the uppermost floor 10 has a relatively long insulated section 37 at its upper end, and the rod for the first floor has a similar insulated section at its lower end. By this arrangement there is no danger of the elevator being carried beyond 15 the given point upwardly or downwardly. After a certain floor has been selected for the car to stop at, a change can be made to any other floor while the car is in motion, by proper operation of the lever 31. In case 20 of an emergency the car can be stopped at any point by moving the lever so as to be out of contact with any of the terminals. If the car has been stopped at the desired floor, and it is decided to go farther in the same 25 direction, this is accomplished in the same way, by a proper manipulation of the lever. In case the momentum of the elevator carries it over the insulation when going in either direction the resulting contact of the roller 30 with the other section of the rod will cause a reversal of the movement, bringing the car to rest at the proper point.

As a matter of convenience the terminals 28 are numbered consecutively, to correspond 35 with the numbers of the floors to be selected thereby.

The wires 27 may be passed through a conduit 39, as shown in Fig. 1, such wires being properly insulated from each other.

40 What I claim, and desire to secure by Letters Patent, is:

1. A control mechanism for the electrical operating system of an elevator, arranged to move an elevator either upwardly or downwardly, comprising a series of rod conductors forming a part of said system, each provided with an insulated section, said sections arranged in staggered relation, and a plurality of contact members movable on said 45 rods, also connected with said system, capable of forming independent circuits through said conductors, to be interrupted upon such contact members coming into engagement with said insulated sections, the conductor 50 sections on opposite sides of said insulated sections forming independent circuits adapted to cause a movement of the operative devices in opposite directions.

2. In combination with an elevator, and 60 operating devices thereof, an electrical control system therefor, comprising a series of rod conductors, provided at staggered inter-

vals with insulator sections, those parts of said conductors on opposite sides of the insulators being in independent circuits, capable 65 of causing a movement of the operating devices of the elevator in contrary directions, contact devices movable on said conductors, and adapted to be supported on the elevator; and a selective switch mechanism adapted 70 for support in said elevator, and connected with said contact members, to close a circuit in said control system through one of said circuits, said circuit being broken upon the contact member reaching the insulated section 75 of such conductor; said control system being operatively connected with said operating devices, so as to start the same upon a circuit being closed through one of said conductors, and stop the same upon such circuit being broken.

3. In combination with an elevator and operative devices thereof, including a motor and brake mechanism therefor, an electrical control system therefor, comprising a series 85 of rods provided at intervals with insulator sections, arranged in staggered relation on the several rods, the rod sections on opposite sides of the insulator sections being in independent circuits capable of causing movements of the operating devices of the elevator in contrary directions, contact devices movable on said rods, and adapted for support on the elevator, and a selective switch device carried in the elevator, and connected 95 with said contact members, to close a circuit in said control system through some one of said rods, said circuit being broken upon the contact member reaching the insulated section of such rod, said control system being 100 operatively connected with said operative devices, so as to start the same upon a circuit being closed through one of said rods, and coincidently release said brake, and stop said operative devices upon said circuit being 105 again opened, and coincidently set said brake.

4. In a control mechanism for the operating system of an elevator, a rod conductor provided with an insulated section intermediate its ends, the two parts of said rods being connected through independent circuits with the operating system of the elevator, to cause a movement thereof in an upward or downward direction, as desired, a contact 110 member movable longitudinally of said conductor, an electrical system connecting said contact member with said conductor, on opposite sides of the insulator section, said system being normally open, and means for 115 closing said system through one or other of the ends of said conductor, at will.

In testimony whereof I affix my signature.
MORRIS C. NELSON.
